UNITED STATES PATENT OFFICE.

LEWIS MARTIN KELLOGG, OF LOS ANGELES, CALIFORNIA.

MERCURY AMALGAMATOR.

1,278,163.

Specification of Letters Patent. Patented Sept. 10, 1918.

Application filed January 14, 1914. Serial No. 812,119.

To all whom it may concern:

Be it known that I, LEWIS MARTIN KELLOGG, a citizen of the United States, and a resident of Los Angeles, in the county of 5 Los Angeles and State of California, have invented a new and useful Mercury Amalgamator, of which the following is a specification.

My invention relates to improvements in 10 a mercury amalgamator in which the mercury used for recovering the gold, silver and platinum from their ores, is intensified in its amalgamating properties and prevented from wasting away by flouring and the objects of my invention are to provide a circulation of mercury through a proper vessel having means for properly passing ore pulp upward through the mercury and to afford a certain circulation of the mercury from 15 20 the vessel which will continually carry away with it the scum which may form upon the mercury surface.

I attain these objects in the mechanism illustrated in the accompanying drawings in 25 which—

Figure 1 is a sectional elevation of the entire device taken on the line D, D, Fig. 2.

Fig. 2 is a top view of the entire device.

Similar letters and numerals refer to similar parts throughout the several views.

The mercury pot 1 is a vessel adapted to contain a body of mercury to the height of the dotted line C. At its top is an overflow ore discharge rim 20 beyond which is formed 35 an annular discharge channel 19 having a spout 18 at its lowest part.

Through the wall of the vessel 1 and in proximity to the mercury level C is the mercury discharge port 4 which connects the 40 interior of the vessel 1 with the discharge chamber 5. The chamber 5 is attached to the side of the mercury vessel 1 reaching from below the mercury level C to above the rim 20 and carries the wash water tube 11 with its regulating valve 10 and the mercury discharge conduit 12.

In the bottom of the mercury vessel is the mercury inlet conduit 14 and ore inlet conduit 15.

50 The arms 8 attached to the top of the mercury vessel form a bearing for the hollow shaft 6. This hollow shaft, being rotatably mounted, carries the pulley 7 at its top end and the rotor 13 at its lower end and also carries the wash water tubes 24 and

25 which communicate with the interior of the shaft.

The rotor 13 is suspended into the mercury vessel and positively carries the screen baffles 17. The stationary screen baffles 3 60 are carried in proper settings within the mercury vessel and are held from floating up out of the vessel by the lugs 2.

An anode 22 is carried on the top of the rotor 13 at the level of the rim 20 in electrical communication with the conductor A. In the bottom of the vessel is the cathode 23 carrying the conductor B, by means of the bolt 16. A wash water tube 26 with its regulating valve 9 is carried over the top 70 of the amalgamator, its discharge end terminating in the top of the hollow shaft 6. The rotor 13 is held from floating up out of the vessel 1 by the set collar 27.

In the operation of this amalgamator, 75 mercury is admitted to the vessel 1 by the conduit 14 which rising up to the port 4 flows out through the port into the chamber 5 passing away by the conduit 12. The tube 12 is bent up in the form of a seal to 80 prevent water from passing out with the mercury. The mercury discharging from the tube 12, after being properly filtered and intensified is returned to the mercury vessel by the conduit 14.

85 The rotor 13 is rotated slowly by a belt over the pulley 7 and ore pulp suspended in water on being forced into the vessel through the conduit 15 floats up through the body of mercury carried in the vessel its upward 90 flow being properly interrupted by the rotating screens 17 and stationary screens 3.

The ore pulp and water then rises up from the surface of the mercury and passing out from under the anode 22 overflows the 95 rim 20 passing away by the channel 19 and spout 18.

In the amalgamation of precious metals with raw mercury and even to a greater extent with mercury that has been intensified 100 in its amalgamating properties by the addition of some such chemical as metallic sodium, or with an electric current, or both, a certain amount of scum collects upon the surface of the mercury. This scum is composed of precious metals either in physical or chemical combination, and baser metallic combinations, and mercury and if it is not continuously removed it will accumulate to such an extent that it will break away from 110

the mercury body and pass away with the tailings thus causing a loss in values and in mercury.

In the device herein set forth the scum is continually removed with the out flow of mercury for as the outflowing mercury does not touch the top of the port 4 in its discharge from the vessel the scum upon its surface drifts out into the chamber with it to be caught finally in a proper filter.

It is readily seen that some of the ore pulp would ordinarily flow out over the surface of the mercury from the vessel into the chamber but such an action is frustrated by a flow into the vessel from the chamber through the port 4 over the surface of the outflowing mercury of a small amount of cleaning water which is admitted to the chamber through the conduit 11.

By the rotation of the baffles 17 the body of mercury carried within the vessel is also impelled to rotate, with a lesser velocity, and by its rotation all the scum accumulating on the surface of the mercury is at some time circulated into proximity to the mercury discharge port through which it is then carried out of the vessel on the surface of the discharging mercury.

The chamber 5 with its sealed mercury discharge conduit is so arranged as not to interfere with a free overflow of the mercury from the vessel through the port 4.

In order to avoid the use of a sufficient amount of water, in floating the ore through the mercury, to carry the heavier parts of the ore pulp from the mercury surface over the discharge rim 20, the amount of water used to float the ore pulp is cut down to a minimum and the necessary water for the final discharge of the ore pulp is admitted underneath the anode 22 by the tube 26, hollow shaft 6 and tubes 24 and 25. From these tubes or nozzles the clean water gently impinges downward into the stratum of tailings above the mercury with a stirring effect causing the tailings to overflow the rim 20.

The conditions present in the treatment of different ores and placer ground vary greatly and while one ore might be successfully treated in the device herein set forth with the mercury intensified chemically and another ore would require that the mercury be treated only with an electric current still other ores of a more refractory nature require both the chemical and electrical treatment.

In the present device the necessary flow of a high amperage current is provided for by placing an anode 22 at the top of the vessel, its undersurface being in contact with the overflowing ore and water and the current from a proper source of electric energy, passing to the anode by the conductor A passes down through the water into the

surface, and through the body of mercury returning to its source by the cathode 23 bolt 16 and conductor B. With the use of the electric current the vessel and rotor are made of a material having a lesser conductivity than the mercury.

The screen baffles 3 have cuts in their edges to match the lugs 2 and in cleaning the device pins are inserted down through all of the screens and the rotor turned till the cuts in the screens 3 are right with the lugs 2. The arms 8 are then detached from the vessel and the arms, shaft, rotor and screens lifted away.

The mercury having been withdrawn from the vessel by the cock 21 the vessel and baffles are easily cleaned of amalgam. For the reason that the mercury discharge port 4 is placed in such a position that the scum on the surface of the mercury can flow out on the surface of the outflowing mercury in fact constitutes an overflow mercury discharge from the vessel below the overflow ore discharge over the rim 20.

Having thus described my invention I claim:

1. In combination in an amalgamator an amalgamating receptacle adapted to contain mercury having an overflow ore discharge, a mercury overflow discharge from said receptacle below said overflow ore discharge and extending above and below the mercury level in said receptacle, means for preventing ore pulp from passing out of said receptacle on the surface of the mercury overflowing therefrom, an ore feed means for said receptacle, and means for supplying mercury to said receptacle, all substantially as set forth.

2. In combination an amalgamating receptacle adapted to contain mercury having an ore pulp overflow, a mercury chamber in proximity to said receptacle, a mercury discharge port for said receptacle communicating with said chamber, said port being below the ore pulp overflow and extending above and below the normal mercury level in said receptacle, means for preventing the rise of mercury to the top of said port, means for establishing a current of water from said chamber over the surface of the mercury in said port into said receptacle, a mercury discharge means for said chamber, a mercury feed means for said receptacle and means for feeding ore pulp to said receptacle, all substantially as set forth.

3. In combination, in an amalgamator, a receptacle adapted to contain mercury having an ore pulp overflow, a mercury discharge port for said receptacle below the ore pulp overflow and extending above and below the normal mercury level in said receptacle, means for preventing the rise of mercury to the top of said port, means for establishing a counter current of water over

the surface of the discharging mercury in said port into said receptacle, means for circulating the surface stratum of the mercury in said receptacle into proximity to said port, means for bringing ore pulp into contact with the mercury, a mercury feed means for said receptacle and means for feeding ore pulp to said receptacle, all substantially as described.

LEWIS MARTIN KELLOGG.
